UNITED STATES PATENT OFFICE.

CHARLES E. DATH, OF CHICAGO, ILLINOIS, ASSIGNOR TO WILLIAM H. MINER, OF CHAZY, NEW YORK.

DRAFT-RIGGING FOR RAILWAY-CARS.

1,222,080.

Specification of Letters Patent. Patented Apr. 10, 1917.

Application filed October 23, 1914. Serial No. 863,156.

To all whom it may concern:

Be it known that I, CHARLES E. DATH, a citizen of the United States, residing at Chicago, in the county of Cook and State 5 of Illinois, have invented a certain new and useful Improvement in Draft-Riggings for Railway-Cars, of which the following is a full, clear, concise, and exact description, reference being had to the accompanying 10 drawings, forming a part of this specification.

This invention relates to improvements in draft riggings for railway cars.

An object of the invention is to provide 15 a friction draft rigging which may be employed in connection with stop castings of tandem spring gears.

Another object of the invention is to provide 20 a draft gear of the type above indicated so arranged that the parts may be readily assembled and disassembled and placed in position on the car.

The invention furthermore consists in the 25 improvements in the parts and devices and in the novel combinations of the parts and devices, as herein shown, described or claimed.

In the drawing forming a part of this 30 specification, Figure 1 is a longitudinal vertical sectional view of a draft gear showing my improvements, the draw bar and yoke being shown in elevation. Fig. 2 is a horizontal sectional view taken substantially on the line 2—2 of Fig. 1, the parts 35 being shown in full buff. Fig. 3 is a transverse sectional view on the line 3—3 of Fig. 1. Fig. 4 is a sectional view taken on the line 4—4 of Fig. 1 but omitting the yoke, the sills and stop castings. Fig. 5 is a 40 detail perspective view of the hollow block employed with my improvements, and Fig. 6 is a detail perspective view of the combined friction shell and spring casing.

In said drawing, 10—10 denote the center 45 sills or other draft members, to which are secured the stop castings 11—11, each of which stop castings is provided with tandem arranged stops consisting of front stop 12, rear stop 13, front intermediate stop 14 50 and rear intermediate stop 15. Front and rear intermediate limiting stops 16—16 are also provided in the usual manner. 17 denotes a U-shaped yoke of usual form secured to the draw bar 18 by rivets or other suit-

able means. Mounted within the yoke is my 55 improved gear which, as shown, comprises a combined friction cylinder and spring casing A, shown most clearly in Fig. 6, the friction cylinder being designated by the reference 19 and the spring casing by 20, 60 said cylinder and casing being united by upper and lower horizontal members 21—21, thus providing openings 22 on the sides thereof for a purpose hereinafter specified. The rear end of the spring casing 20 is provided 65 with an integral rear follower 23 and the rear end of the cylinder 19 is provided with an integral front intermediate follower 24. As shown in Fig. 2, a front follower 25 of usual form is employed. Mounted 70 within the cylinder 19 is a friction device which may be of any suitable form and, as shown, the same comprises a plurality of friction shoes 26, wedge 27, with anti-friction rollers 28 therebetween. Engaging the 75 rear ends of the friction shoes 26, is an annular flange 29 formed on the front end of the hollow cylindrical block 30, shown most clearly in Fig. 5. The rear end of the block 30 is provided with outstanding flanges 31, 80 which are seated in corresponding sockets 32 formed on the front face of the rear intermediate follower 33, which follower is so designed that it may be inserted through the openings 22—22 hereinbefore described. 85 The follower 33 is perforated at the center thereof, as is also the rear wall of the block 30, and through these perforations extends a spring 34, which at its front end engages inwardly extending shoulders 35 formed on 90 the friction shoes and at its rear end engages a hollow boss 36 formed integral with the rear follower 23. A connecting bolt 37 is employed which extends between the wedge 27 and said boss 36. Surrounding the 95 boss 36 and having one end thereof pressing against the rear follower 23 is a main spring 38, the forward end of which engages the rear intermediate follower 33.

The draft gear proper is held up by means 100 of carry straps 39—39, which are bolted to the castings 11—11 by bolts 40, the end bolts 40 being slideable back and forth in slots 41 and the intermediate bolt 40 passing through an opening 42 in the casting, which 105 openings 42 at one end are each adapted to receive the bolt and the bolt head fitting between the upstanding lugs 43 and thus sup-

port the carry strap 39. A tie plate 44 is also employed which is bolted to the horizontal lower flanges of the sills 10-10.

By forming the rear intermediate follower 33 separate from the casting A, I insure the more even distribution of the shocks to the stop castings, since it is apparent that the followers 33 and 23 will accommodate themselves to the stops with which they are adapted to coöperate, under all conditions of spacing, which is not always true in a structure where the rear intermediate follower is formed integral with the same casting having the rear follower and front intermediate follower.

The operation of the device is as follows:—Upon buffing movement, the front follower presses back the friction devices, which in turn press the rear intermediate follower backward through the intermediary of the hollow block 30, the resistance of this movement being furnished by the springs 38 and 34. Upon draft, the followers 25 and 33 are in engagement with their corresponding stop shoulders 12 and 15 and the casting A is moved forwardly. Upon the continuation of the forward movement of the casting A, the main spring 38 is compressed against the follower 33, but in view of the fact that the follower 33 can not move forwardly, the pressure from the spring 38 is not transmitted to the friction shoes 26. A slight spring pressure is transmitted to the friction shoes by the secondary or smaller spring 34, which causes a slight frictional action between the shoes and the friction cylinder. In other words, under buff, the friction shoes are resisted by the two springs 34 and 38, whereas, under draft, only the smaller spring comes into play against the friction shoes, thus giving an easy draft action which is desirable, and a heavier buffing action.

I claim:—

1. In a draft rigging for railway cars, the combination with tandem stop castings, of a longitudinally movable friction shell, friction elements and springs within said shell, a front follower, a rear follower, a front intermediate follower, and a removable, rear intermediate follower extending transversely through said shell intermediate the ends thereof and arranged to coöperate with one set of intermediate stops on said stop castings, said rear intermediate follower being movable rearwardly under buff.

2. In a railway draft rigging, the combination with tandem stop castings, of a longitudinally movable combined friction shell and spring casing, friction elements and springs within said shell and casing, a removable intermediate follower extended

transversely through said shell, and a plunger extending between said friction elements and said removable follower.

3. In a draft rigging for railway cars, the combination with tandem stop castings, of a combined friction cylinder and spring casing having shoulders coöperating with one set of end stops and one set of intermediate stops on said castings, and two removable followers coöperable with the remaining sets of end and intermediate stops on said stop castings.

4. In a draft rigging for railway cars, the combination with tandem stop castings, of a slidably mounted combined friction cylinder and spring casing, friction shoes and a wedge mounted within the friction cylinder, a spring mounted within the spring casing, a rear intermediate follower extending through said combined cylinder and casing and intermediate the same and engaging the front end of said spring, and a hollow block extending between the rear ends of the friction shoes and the front face of said intermediate follower, said block being detachable with respect to said follower.

5. In a draft rigging of the character described, the combination with a friction shell, of friction shoes and a spreader therefor coöperable with said shell, a main spring and a secondary spring, the latter acting directly on the shoes under both buff and draft, and means intermediate the main spring and said shoes arranged to transmit the movement of the shoes to said main spring under buff only.

6. In a draft rigging of the character described, the combination with a friction cylinder, of friction shoes and a spreader therefor, coöperable with said cylinder, and two springs, one of said springs resisting movement of the friction shoes under both buff and draft and the other spring resisting movement of said shoes under buff only.

7. In a draft rigging of the character described, the combination with a friction cylinder having friction shoes and a wedge coöperable therewith, of two springs arranged in line with said shoes, both of said springs operating to resist movement of the shoes under buff, and means interposed between one only of said springs and the friction shoes to prevent said spring from coacting with the shoes under draft, said spring being compressed under draft without coacting with the shoes.

CHARLES E. DATH.
